(57) **CLAIM**

The ornamental design for a finger flange, as shown and described.

DESCRIPTION

FIG. 1 is a bottom and rear perspective view of a finger flange in accordance with a first preferred embodiment of my design;

FIG. 2 is a rear elevational view thereof;

FIG. 3 is a front elevational view thereof;

FIG. 4 is a bottom plan view thereof;

FIG. 5 is a top plan view thereof;

FIG. 6 is a left side elevational view thereof; and,

FIG. 7 is a right side elevational view thereof.

The broken lines in the figures show portions of the finger flange that form no part of the claimed design.

1 Claim, 4 Drawing Sheets
